United States Patent Office.

THOMAS SAYLES, OF CHICAGO, ILLINOIS.

Letters Patent No. 99,354, dated February 1, 1870.

IMPROVED RAILWAY-CAR-JOURNAL LUBRICATOR.

The Schedule referred to in these Letters Patent and making part of the same.

I, THOMAS SAYLES, of the city of Chicago, in the county of Cook, and State of Illinois, have invented certain Improvements in Car-Journal Lubricators, of which the following is a specification.

Nature and Object of the Invention.

This invention has for its object an improved method of constructing a lubricator for oiling railroad-car journals.

Description of the Accompanying Drawings.

Figure 1 is an end view of a journal, and position of lubricator under the journal, and the method of attaching the coiled-wire spring to the plate.

Figure 2 is a sectional view of the lubricator, showing the method of attaching the oil-pad to the plate.

I made an application for a patent on an improved lubricator for railroad-car journals, in the latter part of September, 1869, which application is now pending. This application is for improvements not embodied in that application.

General Description.

G is the jacket, made of coarse hemp, or other suitable material.

C C is the oil-pad, working under the journal. This is in two divisions.

D is a wick, for conducting the oil to the pads. It is made of ordinary lamp-wick.

B is the wire which holds and attaches the oil-pad to the plate H.

I I are arms, extending from the plate up, on both sides of the journal, to keep the lubricator in position.

A is a part of the plate, turned downward, with the lower corners thereof turned out, so as to pass under the top wire of the coiled-wire spring O O, thus fastening it to the spring.

This coiled-wire spring O is placed under the plate H, and presses the plate H, with its pads C C, up against the journal.

In making the plate H, I take a piece of galvanized sheet-iron, or any other suitable metal, a little longer than the width of the inside of the journal-box, and of suitable width, which may be a little narrower than the length of the journal.

On each corner of the plate, I leave a strip, I I, fig

2. The space between these strips I turn down. The strips I I, I turn up, and the corners of the part that is turned down I turn out, so as to fit under the top wire of the coiled spring, as shown at A, fig. 1.

The jacket G is made to surround the coiled spring H, and extends from the top to the bottom.

The pads C C rest upon the plate H, and the wick D passes between them. These pads and the wick are fastened to the plate by the wire B, which extends through them, and down through the plate. The two ends are drawn down, and twisted together beneath the plate. This wire is drawn so tightly that the upper pad extends above it considerably, as shown in fig. 2, so, in use, the upper pad will be largely worn before the wire is reached. One pad can be dispensed with, and the wick placed beneath the pad remaining.

K is a support, made of twine, wire, or any suitable material, extending across the base of the coiled spring, and through the wick D, at its lower end. This holds the wick in position, so its lower end is constantly in the oil, in which position it discharges its duties, in supplying the pads with oil, to the best advantage.

F is a projection from the plate H, and when the lubricator is in position, it extends beyond the end of the journal, on the under side, and serves to indicate the condition of the pads.

The operation of my invention is to place the lubricator beneath the journal, and within the journal-box. Oil is then poured into the oil-box. The action of the wick D keeps the pads C C constantly saturated with oil, and they, in turn, being pressed snugly against the journal, by the coiled spring O O, keep the journal constantly lubricated.

Claims.

1. Fastening the pads to the plate H, by means of the wire B, substantially as shown and described.
2. Fastening the coiled spring O to the plate H, as shown and described.
3. Combining the support K, wick D, and jacket G, in manner and for the purpose described.

THOS. SAYLES.
